UNITED STATES PATENT OFFICE.

GORDON SIMMONS, OF BALTIMORE, MARYLAND, ASSIGNOR OF ONE-HALF TO A. D. L'ESPERANCE, OF BALTIMORE, MARYLAND.

SYSTEM OF COMBUSTION CONTROL.

Application filed June 6, 1923. Serial No. 643,677.

My invention relates to an improved system of combustion control, and has for its object an improved system of controlling the generation of steam in a steam generating plant.

A further object of my invention is the providing of an automatic system of control of steam generating plants.

A further object of my invention is a temperature system of combustion control.

A further object of my invention is an alarm indication of combustion conditions in a steam generating plant.

With the foregoing and other objects in view, my invention consists of the methods employed, combination and arrangements of systems and improvements thereof, alarms and indicating means as hereinafter specifically described and illustrated in the accompanying drawings, wherein is shown the preferred embodiment of the combination of systems and indicating means of my invention, but it is understood that changes, variations, and modifications may be resorted to which come within the scope of the claims hereunto appended.

In the drawings hereunto attached is shown an apparatus arranged to carry out the various objects of my invention, but I do not wish to be limited to the arrangement shown nor the apparatus or means shown, as there are various ways of accomplishing the various functions of the installations by vastly different appliances.

For a better understanding of my invention, I have shown in Fig. 1 an installation of a return tubular boiler, stoker fed, as may be found in a modern steam plant, with the various controlling features illustrated as I have installed the same, including certain new features which I will describe and claim hereafter in other applications.

Figure 2 is a theoretical diagram of a single tube of a boiler plant, for technical discussion better to understand the various functions involved in this application, and Figure 3 is a diagram of a boiler in its relative position to the stack control, especially when a plurality of boilers are used in battery, and shows a modified form of damper and fuel control.

Figure 4 shows the entire apparatus combining the control of a single boiler with a battery control.

Similar numerals refer to similar parts and appliances throughout the several views.

1 is a boiler, in Fig. 1, return tubular. 2 is the stoker. 3 is the stoker operating means which in the drawings is shown as a steam engine. 4 is the stoker operating control means, which in the drawing is electrically controlled by mechanism hereinafter described. 5 is an improved bridge wall permitting the introduction of air at a desirable point in the combustion chamber. 6 is the air inlet control damper operated by electro-magnetic controlling means, 7 and the uptake damper 8 is in a similar manner operated simultaneously therewith in the layout shown in Fig. 1. 9 is a thermocouple in the combustion chamber. 10 is a thermocouple in the exit gases. 11 is a temperature recording controller well known in the art, such as the Taylor instrument or similar device as manufactured by the Leeds & Northrup Company, illustrated in Brewer Patent #1,356,804, of October 26, 1920, which I have adopted and by certain changes in the connections, and improvements which I will more definitely describe in another application made applicable for adoption to the subject matter of this application. Two such controllers may be used for simplified connections, as found commercially. 12 is an electrical relay for operating stoker operating control means 4 which is shown in the drawing as an electrically operated steam valve. 13, 14, and 15 are red, white, and blue signal lights respectively. 16 is a klaxon horn. 17 is an inlet duct in the bridge wall surmounted by a perforated refractory tile 18 for diffusing the air and heating same.

When a water tube boiler is used, it is difficult or almost impossible to use a thermocouple in the combustion chamber. I avail myself of the well known principle that the flue gas content of CO_2 is a function of or varies as the theoretical temperature of combustion, the CO_2 content being measured by the thermal conductivity of the products of combustion, with reference to air. I use this means which is accurate for all practical purposes, in conjunction with my actual temperature readings of the exit gases to accomplish the various objects claimed by connecting in place of the thermocouple 9 as shown in Figure 1, an electrical CO_2 cell in the passage of the gases.

This apparatus I have shown at 19 and it may be connected to the temperature recording controller 11 at the same terminals as thermocouple 9 which is in the combustion chamber, and they will practically replace each other in the operation of my apparatus.

The operation of my apparatus is as follows:—Fig. 1 shows an ordinary return tubular boiler in partial sectional elevation, 10 with a thermocouple located at each end thereof. The temperature as measured in the combustion chamber at "A" is a function of the temperature of combustion and is always less than this temperature, and is 15 within the safe working limits of the thermocouple to stand, which makes this method a practical one. Furthermore, a variation in the temperature of combustion promptly affects the thermocouple so located, there being little "lag" and it has been found that if a temperature at this point is maintained between 1,700 degrees Fahr. and 1,800 degrees Fahr. that a reasonably high temperature of combustion is maintained, but not 20 too high, which might clinker the coal, burn grate bars, or even effect disastrously the furnace linings.

A substantial part of the heat of the fuel is delivered directly to the boiler by radiation, and some of the heat is also radiated 30 to the boiler setting and rejected to the ash pit. This loss is unavoidable, and its elimination is not contemplated by this method.

What is contemplated is, the substantial 35 maintenance of two fixed temperatures at two definite locations in the gas passages of a boiler installation, in combination with a uniform steam pressure, which can be demonstrated to mean depending upon the 40 temperatures held;—

A definite combined boiler and furnace efficiency.

A reasonably definite temperature of combustion.

45 A definite and known heat loss to the stack.

A definite ratio of air to steam, or in other words, the control of air supply to the furnace in step with the steam flow from 50 the boiler.

It further becomes apparent that when burning a low grade, low ash fusing coal, that if combustion chamber temperature is held at a sufficiently lower temperature than 55 would be usual in the case of a high grade coal, clinkering can be reduced to any determinable extent or eliminated if the ash fusing point of the coal is known and the temperature of combustion kept below such 60 temperature by proper setting of the control points in 11.

This is accomplished by ascertaining a 65 number of different furnace temperatures with an optical pyrometer and simultaneously reading the corresponding tempera-

tures at thermocouple 9, and plotting a curve showing the relationship between these temperatures, from which curve the relationship between the fuel bed temperatures and corresponding thermocouple readings can readily be read.

70 Since it is known that the maintenance of a temperature on the grates only fifty degrees lower than the fusing point of the ash, no clinker is obtained, the clinkering of the coal under this method is controllable.

Referring to Fig. 2 showing a single boiler tube surrounded by a cooling medium as water, both at a fixed temperature. The arrows show the path of the gases of combustion and the thermocouples located at each end thereof, measure in this particular case and for this discussion, 1,800 degrees Fahr. and 500 degrees Fahr. respectively, giving 80 an actual working condition observed.

85 We then have in a sense, what amounts to a Venturi meter, where in place of a pressure drop, we measure a temperature drop. And since we are interested in heat delivery to the cooling medium, in this case, water 90 under approximately 125 lbs. pressure at a temperature for this discussion, 350 deg., we have an efficient form of "heat meter".

The principle of its operation is based 95 upon the well known law of heat transfer when heated gases flow through or around a boiler tube, as follows:—The heat available for absorption is proportional to the product of the weight of the gases flowing and the difference in the temperature of the gases 100 and the wall of the tube.

Therefore, if a substantially constant difference in temperature is maintained between the point of ingress and egress of the gases, as at "A" and "B", the heat available 105 for steam generation is proportional to the weight of the gases flowing.

If the air supply to the furnace is so controlled by the incremental movement of the main stack damper caused by slight variations in the steam pressure or other means, in combination with the incremental movement of the individual boiler damper actuated by temperature controlled means, that a substantially constant and predetermined 115 temperature at "A" is maintained, the number of pounds of air will be in a definite ratio to the number of pounds of steam, which ratio can be varied to suit any condition depending upon the adjustment.

120 If the temperature of the gases at "B" is maintained at say 500 deg. Fahr. or lower, depending upon the load on the boiler, it is at once evident that the boiler is reasonably clean of scale and soot.

The particular point to be brought out in this discussion is that with a clean boiler and not an excessive overload, the temperature of the gases at this point, "B" is a 125 function of the excess air.

If we assume that while holding the above temperatures at the above named two points, that we have an efficient furnace condition, with a minimum of excess air, if a hole in 5 the fire develops or the fire becomes excessively thin, the volume or weight of gases flowing becomes greatly increased and as the cross section of our tube area remains constant, the velocity of the gases must proportionately rise and in combination with the dilution of the heat of the gases caused by the aforementioned excess air, the above named temperatures are not maintained. The temperature at "A" drops and assuming 10 there is a reasonable load on the boiler, the temperature at "B" rises.

This phenomenon is used as the basis for an alarm indication of excess air, and in combination with the other apparatus and 20 means shown can be made to control said combustion conditions. It is worthy of note that the alarm indication of high stack temperatures also functions for sooty flues or high overloads and the reason is manifest. 25 In well operated plants the flues are regularly blown and ample number of boilers are used to prevent a greatly overloaded condition. 125 to 175 per cent of builder's rating appears to be the efficient operating load of 30 the average boiler.

Again referring to Fig. 1 and the stoker control as shown, the particular installation as installed provides for a greatly lessened coal feed when the temperature at "A" exceeds 35 1900 deg. Fahr. Manifestly the coal feed can, by suitable well known electric solenoid valves and relays, be varied at will by the said temperature actuated means included in the commercial recording temperature controller illustrated at the top of Figure 1, controlled by the temperatures at "A" or 40 "B" or both in an almost infinite number of combinations, and similarly a great number of different means can be used for controlling the air supply from a temperature difference caused by the passage of the products of combustion through the boiler.

In the particular installation shown in Fig. 3, the individual stoker engine speed 50 for each boiler is varied by the usual balanced steam valve in the steam line operated by a differential lever 20, one side of the lever being connected by chain to the damper regulator 21 operating main stack damper 55 22 by variations in steam pressure, and the other side of lever 20 connected also by chain to the piston of a regulator 23 operated by a pilot controlled in turn by a diaphragm affected by changes in the overfire vacuum 60 from overfire vacuum. The balanced valve 24 is connected to the center of the differential lever 20 so that equal movements of the lever in opposite directions will cause no movement in the controlled valve.

65 Assuming then, a low steam pressure and

a thick fuel bed, the amount of opening of the valve 24 and the consequent stoker speed will be very much less than with a low steam pressure and thin fuel bed.

High combustion chamber temperature as 70 at "A" does not necessarily mean high efficiency. It may mean that the zone of chemical combination of the combustible with the oxygen present, has been moved further back near the tubes, and the result of this is that 75 complete combustion is arrested at this point with consequent fuel loss and smoke. The relay 12 and solenoid steam valve 4 as shown in Fig. 1 retard the coal feed when this condition occurs.

80 Separate control points in the temperature recording controller 11, operate the red, and white signal lights over boiler. In this particular installation and so the operation can be more easily understood, we will assign 85 different temperatures for the different control points. The red light will show from zero to 1600 deg. F. The red and white lights showing a fair combustion condition, will both light from 1600 to 1700 deg. F. 90 The white light only will show above 1700 deg. F. showing good combustion, and the stoker valve will close at 1900 deg. F.

95 The blue light is operated only by the temperature of the exit gases of its particular boiler. The klaxon in series with the common wire to all blue lights, is common to the battery of boilers, but in the drawing Fig. 1 is across the blue light circuit as that is for a single boiler. The controller operates the 100 blue light and klaxon at 580 deg. F. at point "B." A separate controller as they are found commercially would be necessary to control from point "B."

105 The magnetic regulators 7 operated across the red and white signal lights, said lights 13 and 14 being operated intermittently, control the individual boiler dampers 8. Manifestly, when both red and white lights are on, the regulator is inoperative since the 110 magnets 26 oppose each other and the two opposed springs 27 hold armature and pilot valve 28 in neutral position. Choke valves 25, hand adjusted, makes the movement of the damper sluggish and weight 29 provides for quick opening and slow closing until it strikes against a stop (not shown), set to prevent the fires assuming a banked condition, in other words to prevent the dampers from fully closing.

115 The main damper regulator 21 prevents popping and governs the position of the damper 22 in accordance with the steam pressure.

This system of control then, is designed 125 to accomplish the following objects:—

To assign the bulk of the load to those boilers whose fires are in better condition to carry it.

To notify fireman by red light that damper 130

on particular boiler is gradually closing account improper condition of fire or falling off in load.

To warn fireman by blue light over particular boiler and by the klaxon horn, that flues are foul, boiler is overloaded, or a preventable amount of excess air is present account of hole in his fire, thin fuel bed, fire door open, or automatic damper control not 10 operating.

Automatically to slow up stoker engine when temperature in combustion chamber becomes too high for good efficiency, fusing point of the coal or the fire brick.

15 To notify fireman which fires are in good condition so that he can work on the fires most needing his attention.

To automatically control and maintain efficient combustion conditions without outside intervention, it being the fireman's duty 20 to keep coal hopper full and periodically remove the ash.

In Figure 4, I have shown in a single figure the entire apparatus combining the 25 control of the single boiler as shown in Figure 1, with a battery control as shown in Figure 3. The operation of the device is as follows: The various devices are set to give proper control with a definite kind of coal, a definite overfire vacuum and a definite steam pressure. The device 23, which is well known, will maintain the damper 6 in such position that the overfire vacuum is at the predetermined figure, we will say a one-tenth of an inch, and the device 23 maintains such tenth of an inch vacuum under any and all conditions. In order to understand the device a little more clearly, we will first eliminate the damper 8 from consideration 30 as if it were entirely missing. The fuel bed becomes thin and the device 23 thereupon acts to close slightly the damper 6 in order to maintain the overfire vacuum of one-tenth inch. A lower steam pressure probably 35 results, and this causes the Mason steam pressure regulator 21 (this also being well known) to operate the battery damper, opening this damper and simultaneously raising the left hand end of the equalizing lever 20, 40 the right hand end of which has been raised slightly by the closing of the damper 6, the result being that each of these movements tends to open the balanced valve 24 and to cause the stoker engine 3 to feed fuel at a 45 faster rate.

Under certain circumstances, the regulator 21 is not called upon to act since the raising of the lever 20 by the closing of the damper 6 will itself cause the proper correction in stoker speed so as to build the fire bed to the proper thickness. The regulators 21 and 23 operate together to govern the valve 24 and usually in conjunction, but if by chance the requirements for steam 60 should drop when the damper 6 is being

closed due to the thinning of the fire bed, no change in the stoker engine speed would be required, and the proper compensation would be obtained by the simultaneous raising of the right hand end of the lever and 70 the lowering of the left hand end of the lever.

We will assume, as in the first instance, that the steam pressure regulator 21 which operates incrementally has operated to open 75 the main damper 22. This will cause an increased differential pressure through the flues of the boiler, and this increases the negative pressure at the location of the damper 8, since the pressure at the location 80 of the instrument 23 is constant, and consequently the rate of flow of gas through the boiler changes irrespective of the condition of the fuel bed, and this change is at a definite rate corresponding to the definite 85 change in steam pressure affecting the instrument 21. Assuming the right hand side of lever 20 to be fixed, the fuel feed, through its connection from the instrument 21 to the left hand side of lever 20, will also vary the 90 stoker speed at a definite rate with definite changes in steam pressure affecting the instrument 21, and, therefore, the rate of feeding fuel and the rate of flow of gases through the boiler are in definite ratio one to the 95 other.

Assuming, however, that due to change in pressure of the steam operating the stoker engine 3 or a variation in the friction load, 100 would cause this ratio of gas flow to fuel feed to vary from the predetermined rate. The left hand side of lever 20 will compensate for such changes in stoker speed so that fuel will be fed at the rate at which it is burned because if the fuel bed should become too thick because the fuel was not being burned at the rate fed, damper 6 would necessarily open to maintain the fixed overfire vacuum of one-tenth of an inch, 105 through the instrument 23, and this in turn would cause the right hand side of lever 20 to lower, slowing up stoker speed until the fuel already fed was consumed. In the event of fuel being burned at a more rapid rate than being fed by stoker 3, the pressure necessary to overcome resistance of the fuel bed would not be so great, and instrument 23 would slightly close the damper 6 as previously explained, raising the right hand side of lever 20, causing stoker engine 3 to 110 feed fuel at a more rapid rate to replace fuel already burned.

We will now replace individual uptake damper 8 controlled by instrument 7, which is actuated by mechanism which is in turn controlled by instrument 11 and actuated by instrument 19. As long as the CO_2 content of the combustion gases remains at a predetermined standard, no change in the position of damper 8 will occur. We will as 115 120 125 130

sume, however, the CO₂ which indicates that the rate of feeding air and fuel is not being maintained at the predetermined standard, or that the quality of the fuel has changed or that a hole in the fire has occurred. This would cause the Shakespear CO₂ cell to operate the device 11 which governs the instrument 7, controlling in turn the position of the furnace uptake damper 8. If the CO₂ content has dropped, the damper 8 will close slightly and progressively at timed intervals until the CO₂ content is returned to normal.

The closing of the damper 8 will reduce the rate or volume of the gases through the furnace and consequently, affect the over-fire vacuum and through the instrument 23 will close under incremental movements the damper 6, causing an increased speed of the stoker engine. If, instead of falling, the percentage of CO₂ should arise, the Shakespear cell 19 would cause the damper 8 to open by means of the devices 11 and 7 in the same manner, that is, by incremental movement of the damper 8, or these parts could be arranged so that upon increase in the CO₂ content, the damper 8 would open wide. Should the CO₂ content continue to rise so that the damper 8 remains in wide open position, the Shakespear cell 19 would operate the instrument 11 and relay 12 to close the electrically operated steam valve 4, slowing the speed of stoker engine 3 to an idling speed or stop it altogether, this, of course, being absolutely independent of the position of the balanced steam valve 24, and such action will obviously cause lowering of the CO₂ content until normal CO₂ ratio is had, at which time the electrically operated valve 4 will again open wide, leaving the control of the stoker engine entirely with the balanced valve 24.

Having thus described my invention, what I claim and desire to secure by Letters Patent is:—

45 1. The combination with a boiler, a furnace, fuel feeding means, and air control means, of mechanism for governing both of said means to maintain a predetermined temperature difference between two definite locations in the gas passage.

50 2. The combination with a boiler, a furnace, fuel feeding means, and air control means, of mechanism for governing both of said means to maintain a predetermined tem-

perature difference between the front and rear ends of the boiler.

3. In a boiler assembly, a furnace, a boiler, an automatic fuel feeder, means controlled by the combustion chamber temperature for controlling the fuel feeder speed as a function of the steam pressure and of the over-fire vacuum.

4. In a boiler assembly, a fuel feeder, a governing means therefor, a differential mechanism connected to said governing means, means governed by the steam pressure, means governed by the over-fire vacuum, and means for connecting each of said last two mentioned means separately with said mechanism so that they act in conjunction or in opposition to alter the position of said fuel feed governing means.

5. In a steam generating plant, an automatic fuel feeder, an air supply means, steam pressure responsive means, over-fire vacuum responsive means, temperature responsive means, means governed by the last three mentioned means for controlling the air supply means, and means governed by the steam pressure responsive means and by the over-fire vacuum responsive means for controlling the fuel feeder.

6. In a steam generating plant, means for controlling the rate of supply of air to the furnace, means responsive to changes in the combustion chamber temperature for governing said air control means, steam pressure means independent of said last mentioned means for modifying the control of the air supply means, and over-fire vacuum responsive means acting in conjunction with said temperature responsive means to alter the ratio of flow of air to the furnace.

7. In a boiler assembly, a device responsive to changes in steam pressure for altering the rate of supply of air, and means responsive to changes in the rate of supply of air for altering the rate of supply of fuel to maintain such rate of supply of fuel in a definite ratio to the rate of supply of air.

8. In a system for maintaining a definite ratio of fuel to air in a steam generating plant, an automatic fuel feeder, and means responsive to changes in the rate of air flow and in steam pressure for altering the rate of fuel feed.

GORDON SIMMONS.
